LOGARITHMIC DISCRIMINATOR

Raymond U. Sims, Pittsburgh, Pa., assignor, by mesne assignments, to the United States of America as represented by the Secretary of the Navy

Application August 12, 1952, Serial No. 304,036

2 Claims. (Cl. 321—27)

The present invention relates to measuring instruments, more particularly to instruments in which the indication given is substantially a linear function of the logarithm of the quantity measured.

Previous logarithmic measuring devices have been objectionable because they are comparatively more complicated thereby requiring more components and because they have a relatively low conversion efficiency. An illustration of previous type circuits is shown in the publication "Electronics" June 1949, pages 96 and 97, in an article by Harry M. Crain, entitled, "Low frequency discriminator." Many others of the circuits heretofore proposed have been relatively unstable or difficult to manufacture with the desired overall characteristics.

An object, therefore, of the present invention is to provide a logarithmic discriminator capable of producing a typical discriminator S curve on a logarithmic frequency axis for greater range in frequency.

Another object is to provide a logarithmic discriminator the output of which is a substantially linear function of the logarithm of the frequency input.

A further object is to provide a logarithmic discriminator that utilizes relatively few components and which is convenient to manufacture.

Still another object of the present invention is to provide a logarithmic discriminator that has a comparatively high conversion efficiency.

A final object of the present invention is to provide a logarithmic discriminator that is stable in its characteristics.

Other objects and many of the attendant advantages of this invention will be readily appreciated as the same becomes better understood by reference to the following detailed description when considered in connection with the accompanying drawings wherein:

Fig. 1 is a circuit diagram of one embodiment of the invention; and

Fig. 2 presents curves illustrating the basic principle of the invention.

Referring now to the drawing wherein like reference characters designate like or corresponding parts throughout the several views, there is shown in Fig. 1, the circuit diagram of the logarithmic discriminator including the variable frequency source 11 which energizes condenser C₁₂ and resistor R₁₃ in series, which form a branch. The voltage developed across resistor R₁₃ as applied to plate 14 of diode rectifier 15, which has its cathode 16 feeding into the cathode load circuit 17, comprising resistor R₁₈ and condenser C₁₉ in parallel. Resistor R₂₀ and condenser C₂₁, which form a second branch, are energized in series by source 11. The voltage developed across condenser C₂₁ is applied to plate 22 of diode rectifier 23. Cathode 24 of diode 23 feeds into the common cathode load circuit 17. The voltage developed across the cathode load circuit 17 is represented by e₁₇. Condenser C₂₅ and resistor R₂₆, in series, form a third branch, and are similarly energized by variable frequency source 11. The voltage developed across resistor R₂₆ is applied to plate

2

27 of diode rectifier 28. Cathode 29 of the diode 28 is connected to cathode load circuit 30, comprising condenser C₃₁ and resistor R₃₂ in parallel. In like manner resistor R₃₃ and condenser C₃₄, in series, form a fourth branch, and are energized by the variable frequency source 11. The voltage developed across condenser C₃₄ is applied to the plate 35 of diode rectifier 36. Cathode 37 of diode 36 feeds into common cathode load circuit 30. The voltage developed across the cathode load circuit 30 is represented by e₃₀. The output voltage measured at output terminals 38 will be equal to e₃₀ minus e₁₇.

In deriving the relations that exist in the circuit of the present invention the following symbols will be used:

E=voltage applied to the circuit

e=resultant voltages

R=resistance

C=capacitance

t=time

f=frequency

w=angular frequency ($2\pi f$)

ϕ =phase angle of impedance

With the foregoing in mind and referring to the accompanying figures the theory of operation of the device is as follows:

When a sinusoidal voltage of constant amplitude and variable frequency is applied to a series circuit, the voltage across the resistive element is

$$e_R = \frac{ERwC \sin (wt + \phi)}{[(RwC)^2 + 1]^{\frac{1}{2}}} \quad (1)$$

while the voltage across the condenser is

$$e_C = \frac{E \sin \left(wt + \phi - \frac{\pi}{2} \right)}{[(RwC)^2 + 1]^{\frac{1}{2}}} \quad (2)$$

Let us consider two such series circuits, as condenser C₁₂ and resistor R₁₃ and resistor R₂₀ and condenser C₂₁, in Fig. 1, both of which are energized by voltage source 11. Let diodes 15 and 23 be connected to rectify the voltage developed across resistor R₁₃ and condenser C₂₁, respectively, and thereafter feed rectified current into the parallel circuit 17, comprising resistor R₁₈ and condenser C₁₉. Let us assume that the angular frequency w of the voltage or signal, E applied at input terminals 11 varies according to the following conditions:

If w is initially less than

$$\frac{1}{R_{20}C_{21}} \quad (3)$$

and

$$R_{20}C_{21} \text{ is greater than } R_3C_{12} \quad (4)$$

then as w increases, the reactance of C₂₁ decreases, thereby decreasing the voltage applied to plate 22 of diode 23. This decreasing voltage causes the conduction of diode tube 23 to diminish, thereby lowering the voltage e₁₇ developed across the parallel circuit 17. As w increases e₁₇ decreases until

$$w = \frac{1}{R_{13}C_{12}R_{20}C_{21}} \quad (5)$$

under which conditions the voltages developed across R₁₃ and C₂₁ will be equal thereby causing tubes 15 and 23 to conduct current equally. When w increases still further the voltage developed across R₁₃ will increase and become greater than the voltage across C₂₁, thereby causing an increase in conduction of tube 15 and resulting in an increasing voltage e₁₇ at the parallel circuit 17. The relations described above can be verified by examining Equations 1 and 2. Fig. 2 graphically illustrates this action wherein the voltages across capacitor C₂₁ and resistor R₁₃ are represented on the graph as e₂₁ and e₁₃ both

of which combine to produce the voltage e_{17} across the parallel circuit 17.

The circuit constants of $R_{26}C_{25}$ and $R_{33}C_{34}$ are similarly chosen so that the voltage across the parallel circuit 30 as represented by the curve e_{30} plotted against the logarithm of frequency, is identical to e_{17} , except that it is displaced along the abscissa scale. It can be seen from Fig. 2, that voltage curve e_{30} is composed of the voltage curves e_{34} , representing the voltage across condenser C_{34} , and e_{26} representing the voltage across resistor R_{26} .

The output voltage represented by curve e_{38} is obtained by taking the difference between e_{30} and e_{17} , at output terminals 38. The separation of angles A and C, of Fig. 2, should be such that angle B, the crossover of e_{17} and e_{30} , is about the same as angles A and C. Satisfying these conditions assures that the output voltage e_{38} is zero at the point of inflection of the resulting S curve.

It can be seen from Fig. 2 that the logarithmic variation of frequency w produces a linear variation of voltage on curve e_{38} , from approximately 2000 C. P. S. to 50,000 C. P. S. By selecting circuit constants in the manner described above the straight line portion of the S curve deviates very little from the ideal over a frequency range of 25 to 1.

Obviously many modifications and variations of the present invention are possible in the light of the above teachings. It is therefore to be understood that within the scope of the appended claims the invention may be practiced otherwise than as specifically described.

I claim:

1. In an electronic discriminator a pair of input terminals adapted to be supplied with electrical energy of variable frequency; a first condenser and resistor series circuit energized by said electrical energy; a first diode rectifier adapted to rectify the voltage across the first resistor; a second resistor and condenser series network energized by said electrical energy; a second diode rectifier adapted to rectify the voltage across the second condenser; said first and second diode rectifier having their cathodes connected together; a first resistor-condenser parallel circuit to store the rectifier output signal and

having an output terminal; a third condenser and resistor series circuit energized by said electrical energy; a third diode rectifier adapted to rectify the voltage across the third resistor; a fourth resistor and condenser series network energized by said electrical energy; a fourth rectifier adapted to rectify the voltage across the fourth condenser; said third and fourth diode rectifiers having their cathodes connected together; a second resistor-condenser parallel circuit to store the rectifier output signal and having an output terminal; the difference in potential between the output terminals being substantially a linear function of the logarithm of the frequency of the electrical energy.

2. A logarithmic discriminator comprising a first branch having a condenser and resistor connected in series, a second branch having a resistor and condenser connected in series, a third branch having a condenser and resistor connected in series, and a fourth branch having a resistor and a condenser connected in series, the resistors and condensers of said branches being connected in the order named, and the branches being connected in parallel and adapted to have applied thereacross an A. C. signal of varying frequency, means for producing a first unidirectional voltage which is substantially equal to the amplitude of the larger A. C. voltage developed across the resistor of said third branch or the condenser of the fourth branch, and means for producing a second unidirectional voltage which is substantially equal to the amplitude of the larger A. C. voltage developed across the resistor of said third branch or the condenser of the fourth branch, the values of the resistors and condensers in said branches being such that the difference between said first and second unidirectional voltages is substantially a linear function of the logarithm of the frequency of the A. C. signal over a substantially wide range.
